MARLIN W. HEILMAN, OF TARENTUM, PENNSYLVANIA.

STERILIZER.

Application filed April 26, 1924. Serial No. 709,223.

My invention relates to sterilizers and particularly to sterilizer flasks such as are commonly used by physicians, chemists, surgeons and others for sterilizing liquids, medicinal preparations, or for segregating cultures against contamination.

Heretofore it has been customary to use a flask having a relatively long, narrow neck for containing the liquid to be sterilized. As 10 at present practiced, a cotton stopper is placed in the mouth of the flask and the entire neck then swathed in steril gauze, which is wound about the neck and over the mouth of the flask many times. The hands of the operator must not touch the cotton or gauze in order to prevent contamination of the mouth of the flask or the neck thereof, and, therefore, the operation is tedious and requires considerable skill.

20 During the sterilizing process, in which the contents of the flask are submitted to heat sufficient to volatilize the liquid, vapors may pass off through the cotton stopper and gauze. After the sterilizing process, the 25 gauze is removed and destroyed because it cannot be reused. As each sterilizing operation requires a considerable quantity of steril gauze, it will be seen that appreciable waste of relatively expensive materials results, and that where such operations are 30 repeated hundreds of times daily in hospitals of moderate size, considerable time, labor and expense is involved in the present method of sterilizing liquids and preserving 35 cultures.

My invention has for an object, the provision of a sterilizing flask that will prevent contamination of the contents of the flask, or the mouth or neck thereof, and which does 40 not necessitate the waste of steril gauze as required by the prevailing process.

Another object of my invention is to provide a steril closure for flasks that may be applied by the fingers of the operator without danger of contaminating the mouth or neck of the flask, and which may readily be handled without danger of dislodging the cover and exposing the contents directly to the atmosphere.

50 Another object of my invention is to provide a closure for sterilizer flasks having the above characteristics in which standard laboratory equipment may be used with but little

alteration, thereby eliminating the expense incidental to the manufacture of special 55 flasks and closures.

A further object of my invention is to provide a flask and closure therefor that may readily be applied to the flask or detached therefrom, and which serves to direct heated 60 steril vapor over the mouth of the flask and along the exterior of the neck, whereby the sterilization of the mouth and neck of the flask is accomplished simultaneously with the sterilization of the contents of the flask. 65

A further object of my invention is to provide the flask and closure with cooperating, integral interlocking devices whereby the closure is firmly held in contact with the sealing seat, and wherein the interlocking device disposed upon the neck of the flask serves as a spout for facilitating pouring 70 from the flask.

These and other objects of my invention, 75 that will hereinafter be made apparent, are attained by means of the sterilizer herein-after described and illustrated in the accompanying drawings, wherein

Fig. 1 is an elevational view of a sterilizer embodying features of my invention, certain 80 portions being shown in longitudinal section.

Fig. 2 is a transverse section through the closure for the sterilizer, taken on the line 85 II-II of Fig. 1, and showing the neck of the sterilizer in plan view.

Fig. 3 is an elevational view of the closure showing a section in a vertical plane disposed at right angles to the sectional plane of Fig. 1.

Fig. 4 is an elevational view of the neck 90 of the sterilizer.

Fig. 5 is a longitudinal section through a portion of a sterilizer showing a modified construction, and

Fig. 6 is an elevational view of a modified 95 form of flask having a substantially flat packing washer seated upon the body thereof.

Referring to the drawings, the device includes a sterilizer flask 6, which, for the purpose of illustration, may be a standard Erlenmeyer flask, with the exception that the mouth of the flask is flared at diametrically opposite points to constitute locking ears 7, that also serve as pouring spouts.

The spouts may be formed by heating the 105 mouth of a standard flask and then forcing

diametrically opposite portions of the neck outwardly by means of a suitable tool, and then properly annealing the heated portion to prevent cracking.

5 In order to provide a steril closure for the flask without necessitating the laborious and wasteful swathing operation previously described, a steril felt washer 8 is slipped over the neck of the flask and seated upon the 10 expanded portion of the flask at the point of joinder of the body and the neck. The expanded portion prevents longitudinal displacement of the washer toward the bottom of the flask.

15 The closure for the flask comprises, preferably, a standard laboratory test tube 9, of slightly greater diameter than the width of the mouth across the spouts 7, and which is of sufficient length that it may rest upon 20 and be pressed into the felt washer 8 when in operative position. In order to positively lock the closure 9 upon the flask and in firm contact with the washer, the closure is provided with diametrically opposite indentations 11, which constitute transversely disposed lugs 12 extending laterally within the closure. The upper surfaces of the lugs 12 are slightly concave at their central portions 13, and are similar in contour to the 25 under surface 14 of the spouts 7. By reason of this construction, the spouts fit snugly into the seats 13, and yieldingly restrain rotary movement of the closure with respect to the flask when in operative position.

30 35 The lugs 12 are formed in a standard test tube by heating the tube and pressing the sidewalls inwardly with a suitable forming tool, and then annealing the tube. Because of the simplicity of construction, standard 40 laboratory glassware, such as flasks and test tubes, may be used in the manufacture of the device commercially, thereby eliminating the necessity for expensive special molds, etc. This feature reduces materially the 45 cost of manufacture.

45 The operation of the sterilizer is as follows: The liquid to be sterilized is placed within the flask and the closure applied, as illustrated in Fig. 1, by first positioning the lugs 12 opposite the spaces between the spouts 7, and then sliding the closure into engagement with the felt washer 8. Rotation of the closure 90° causes the lugs 12 to slip beneath the spouts 7, which securely seat upon the concave surfaces thereof. The sterilizer is then ready for the sterilizing process.

50 The flasks are made of highly refractory glass, in order to withstand the high temperature incident to the sterilizing process. The liquid within the flask is heated by an external application of heat, and vapors pass from the mouth of the flask and surround the exterior of the neck, thereby sterilizing 55 the exterior as well as the interior thereof.

Pressure within the flask is relieved by permitting the steril vapors to pass through the porous felt washer. It is apparent that the neck of the flask is sterilized both interiorly and exteriorly, and that the contents of the 70 flask may be poured from the spout, without danger of contamination.

75 The closure may be removed by turning it through 90°, thereby disengaging the lugs from the spouts. The felt washers may be reused after they have been sterilized.

80 In Fig. 5, I have illustrated a modified form of porous washer of slightly greater external diameter than the closure, and which is adapted to be compressed slightly 85 and fit snugly within the tube.

85 Closures of different length between the open ends and the lugs 12 may be effectively used with such washers. It is obvious that the sterilizer may also be used for the purpose of preserving cultures of bacteria. The 90 felt washers exclude foreign substances and at the same time permit sufficient ventilation.

95 Fig. 6 illustrates the invention applied to a modified form of flask 13 having a substantially spherical body. This form of flask is commonly used by surgeons, chemists and bacteriologists and a flat washer may be used as a sealing member.

100 While I have illustrated but two embodiments of my invention, it will be apparent to those skilled in the art that various changes, modifications, substitutions, additions and omissions may be made in the apparatus illustrated without departing from 105 the spirit and scope of my invention, as set forth in the appended claims.

I claim as my invention:

1. In a sterilizer, the combination with a flask having a body portion and a neck portion having an external projection thereon, of a porous washer surrounding the neck portion and supported by the body portion, and a test tube constituting a closure fitting over and substantially surrounding the neck portion and engaging the washer, and having integral means interlocking with the projection on the neck portion for releasably retaining it in operative position.

110 2. In a sterilizer, the combination with a flask having a body portion and a relatively long and narrow neck portion having a mouth flared at spaced points on the periphery, of a porous washer surrounding the neck portion adjacent the point of joinder thereof with the body portion, and a closure loosely fitting over the neck portion and substantially surrounding the neck portion and engaging the washer, the said closure being provided with integral means interlocking with the flared portion of the said mouth 115 for releasably retaining the closure in operative position.

120 3. A sterilizer comprising a flask having a body portion and a relatively long neck 125

portion, a relatively deep detachable closure fitting over and surrounding the neck portion for preventing contamination of the exterior thereof and for directing vapors along, and in contact with, the outside of the neck portion, and a porous washer snugly fitting around the neck at a substantial distance from the mouth of the neck portion for closing the open end of the closure against the entrance of foreign substances, and permitting the escape of vapors therethrough.

4. A sterilizer comprising a glass flask having a body portion and a neck portion, a detachable glass test tube constituting a closure fitting over and surrounding the neck portion for preventing contamination of the exterior thereof and for directing vapors along, and in contact with, the outside of the neck portion, a yielding porous member snugly fitting around the neck portion and supported thereby for supporting the closure, and integral means in the closure cooperating with the neck for releasably pressing the closure in contact with the porous member.

5. A sterilizer comprising a flask having a body portion and a relatively long neck portion, a yielding washer surrounding the neck portion and held in operative position by the body portion and a tubular closure for the flask closed at one end and fitting over the neck of the flask, and means for releasably retaining the closure in engagement with the yielding washer including an exterior indentation constituting an inwardly extending projection within the closure and

a radially extending spout on the neck for engaging the said projection.

6. A sterilizer comprising a flask having a neck portion provided with a pouring spout, a sealing washer surrounding the neck portion and a closure fitting loosely over and substantially surrounding the neck portion, and provided with an internal projection for engaging the spout and for retaining the closure in engagement with the washer.

7. A sterilizer comprising a flask having a neck portion provided with a pouring spout, a sealing washer surrounding the neck portion, and a closure fitting loosely over and substantially surrounding the neck portion and having its side wall provided with an indentation constituting an internal projection for engaging the spout and for retaining the closure in engagement with the washer.

8. A sterilizer comprising a flask having a neck portion provided at the periphery of its mouth with an outwardly flared portion constituting a retaining lug, a sealing washer surrounding the neck portion, and a closure loosely fitting over the neck portion and supported upon the washer and having an internal projection having a concave seat for engaging the under side of the said lug for releasably retaining the closure in operative position.

In testimony whereof, I have hereunto subscribed my name this 19th day of April, 1924.

MARLIN W. HEILMAN.
